UNITED STATES PATENT OFFICE

MURRAY A. WACHS, OF BROOKLYN, NEW YORK

MOUNTING ANCHOR

Application filed January 17, 1928. Serial No. 247,406.

This invention relates to mountings for decorating pocket books, bill folds, wallets, or the like, and has particular reference to an anchoring device for said mountings.

5 At the present time considerable difficulty has been experienced in securing mountings to the articles to which they are applied, the same being especially so of corner clips. While it is possible to rivet through both 10 leaves of a corner clip or mounting, it is obvious that exposed rivet heads especially on the outer leaves of the clips are objectionable.

The present invention, therefore, comprehends an improved anchoring means for corner clips or other similar mountings which serve to positively secure said clips or mountings in attached relation to the pocket book or other article without marring the appearance of the outer leaves.

20 The invention furthermore comprehends an anchoring means which admits of the application of the clips to the pocket books or other articles by the use of machines designed for this purpose, thereby eliminating, as far 25 as possible, hand operations which are expensive.

Other objects of the invention reside in the simplicity of construction of the anchoring means, the economy with which the same may 30 be produced, and the general efficiency derived from their use.

With the above recited and other objects in view, reference is had to the following description and accompanying drawings in which there are exhibited certain examples or embodiments of the invention, while the appended claims define the actual scope of the invention.

35 In the drawings—

Figure 1 is a fragmentary outer face view of an article decorated with a corner clip or mounting employing an anchoring means constructed in accordance with the invention;

40 Fig. 2 is a sectional view therethrough taken approximately on the line 2—2 of Fig. 1;

Fig. 3 is a similar sectional view of a slightly modified adaptation of the invention;

45 Fig. 4 is an outer face view with parts

broken away and shown in section illustrating a further form of the invention;

Fig. 5 is a sectional view therethrough taken approximately on the line 5—5 of Fig. 4;

55 Fig. 6 is a still further form of the invention.

Referring to the drawings by characters of reference, 10 designates a section or fragment of a pocket book or other article, and 11 a mounting or clip for decorating the corners or edges thereof. The clip or mounting includes outer and inner leaves 12 and 13 connected or joined by a bight 14. At the present time, the edges of the leaves are 60 provided with prongs which are embedded in the article 10 when the clip is applied, but it has been found in actual practice that said prongs while serving to retain the clip or mounting in place for a limited length of 65 time, do not effectually function to prevent displacement of the clip for a practical length of time.

70 In the form of the invention illustrated in Figs. 1 and 2, the article is provided on its 75 inner face with a rivet shank 15 which is drawn from, soldered or otherwise integrally secured to the leaf and which is adapted to penetrate the article 10 as well as to extend through an opening 16 in the inner leaf 13, 80 after which the shank is upset or spun over to form a retaining head 17. This serves to effectually retain the clip in place against displacement without marring the outer surface of the outer leaf 12, so that the same may 85 be suitably engraved or otherwise decorated. In this manner the clip may be applied in the usual way by machines which have been designed for the purpose, the upsetting or heading of the rivet shank being accomplished 90 by a separate operation on another machine.

95 In the form of the invention illustrated in Fig. 3, the inner leaf 13 is formed with an opening 18, and a separate rivet 19 having a pre-formed head 20 is inserted through the article 10 and through the opening 18 in the leaf 13 when the mounting is applied by the machine. After the mounting of the clip on the article with the inner end of the rivet 100 extending through the opening 18, the rivet

is upset or spun over to form a retaining head 21. It thus follows that the pre-formed head 20 is concealed by the outer leaf 12 of the clip or mounting and while the rivet is not attached to the outer leaf its engagement with the inner leaf 13 serves to effectually anchor the clip to the article.

In the form of the invention illustrated in Figs. 4 and 5, the anchoring device consists of a flat strip of material 22 conforming generally to the shape of the clip or mounting but of sufficiently less width so that the same will be completely concealed within the confines of said clip or mounting. The strip 22 is formed with a plurality of integrally formed tongues or prongs 23 preferably cut and bent from the body of the strip and disposed at a right angle thereto so that the anchoring device is applied initially to the outer surface of the article 10 with the prongs 23 extending through the thickness of the article and protruding from the inner surface thereof. The clip or mounting in this instance has its inner leaf 13 provided with openings 24 through which the protruding inner ends of the prongs extend when the clip is mounted. After the mounting operation the protruding ends of the prongs are upset or spun over to form a retaining head 25. In addition to securely anchoring the clip or mounting in place, the anchoring device strengthens or reinforces the corner or edge of the article 10.

In the form of the invention illustrated in Fig. 6, the anchoring device consists of a wire 26 preferably of circular formation in cross-section, which is shaped to conform generally to the shape of the clip or mounting 11 and which is provided with angularly disposed inwardly bent terminals 27. In this instance, the anchoring device is applied to the outer surface of the article 10 with the terminals 27 extending through the thickness thereof and protruding beyond the inner face of the article to be received through openings 28 in the inner leaf of the clip or mounting, when the same is applied to the article. The apertured portions of the terminals 27 are spun over or upset to form retaining heads 29. It is obvious that under suitable pressure exerted on the anchoring device, the main body thereof will be embedded in the article and will be concealed from view by the outer leaf 12 of the clip or mounting.

What is claimed is:

1. In a clip, including parallel outer and inner spaced leaves connected by a bight, means concealed by the outer leaf for positively securing the clip to the object to which it is applied, said means anchored to and extending completely through the object and through the inner leaf of the clip.

2. In a clip, including spaced parallel inner and outer leaves connected by a bight, said outer leaf having a smooth unbroken surface,

means concealed by the outer leaf for positively securing the clip to the object to which it is applied, said means anchored to and extending completely through the object and through the inner leaf of the clip and a head formed on said means at the terminal which extends through the inner leaf of the clip.

3. In a clip of the character set forth of U-shaped construction in cross-section defining spaced parallel outer and inner leaves, anchoring means extending through the inner leaf only and through the article with which the clip is associated for clamping the same thereto against accidental displacement, said means including a flat thin strip of material conforming generally to the shape of the clip and disposed between the outer surface of the article and the inner surface of the outer leaf, and tongues struck therefrom and extending through the article and through the inner leaf only with the terminal projecting beyond the outer surface of the inner leaf formed with an enlargement constituting a head for retaining the tongue in clamped relation thereto.

4. In a clip of the character set forth of U-shaped construction in cross-section defining spaced parallel outer and inner leaves, anchoring means extending through the inner leaf only and through the article with which the clip is associated for clamping the same thereto against accidental displacement, said means including a length of material disposed between the outer surface of the article and the inner surface of the outer leaf, said length of material having its opposite ends bent at an angle and extending through the article and the inner leaf only with the extremities protruding beyond the outer surface of the inner leaf and formed to provide a retaining head.

5. In a clip including spaced parallel outer and inner leaves, anchoring means extending through the inner leaf only and completely through the article with which the clip is associated for clamping the same thereto against accidental displacement, said outer leaf presenting a smooth unbroken surface and serving to conceal from view the anchoring means.

Signed at New York, in the county of New York and State of New York, this 11th day of January, 1928.

MURRAY A. WACHS.
